COMBINATION PLASTIC AND COLOR DECORATING

Anthony B. Heinsbergen, Los Angeles, Calif.

Application October 20, 1933, Serial No. 694,420

4 Claims.

(Cl. 41—24)

This invention relates to a process of decorating walls, or other similar, interior, or exterior surfaces.

One of the objects of this invention is to produce a combined plastic and color decoration while the material of a surface, plaster or other suitable material, is still in a pliable, plastic, or workable condition.

Another object is to inscribe, engrave, cut-in, or scratch-in, any ornament, or design, to various depths, or to press in, or raise, or build up, ornaments or figures, adding coloring matter in form of paints or leaf, gold, or silver, or other metal or the like matter, and add or cut into such work until finished in a desired and required manner according to this invention.

Other objects will appear from the following description and appended claims as well as from the accompanying drawing, in which—

20 Fig. 1 is a fragmentary top plan view of a mural decoration in various colors produced according to this invention.

Fig. 2 is a cross section on line 2—2 of Fig. 1, in enlarged scale.

25 Fig. 3 is a cross section on line 3—3 of Fig. 1, in enlarged scale.

Fig. 4 is a cross section on line 4—4 of Fig. 1, in enlarged scale.

It must be understood that, as a rule, a decorator gets a surface plastered for him, smooth, rough, or medium, and when sufficiently dry, the decorator applies a certain number of coats of paint of one kind or other to produce his objects of ornaments and coloring.

35 On the other hand, also, some designs and ornaments are produced by a casting of plaster or plastic material into forms modeled in clay or other material, and, then, by bringing such finished ornaments into place, after which a desired coloring is applied to the prepared and already finished forms of the ornaments.

40 With this new process, however, a decorator requires the surface to be in a wet or semi-firm condition, and the decorator must require that applications as to the amount and position or point be made according to his directions, and that the condition of the applications in successive steps are suitable for him to ply or model into forms desired by him, to receive eventually desired or required coloring, and that the different applications must be in a condition to remain workable for him.

45 In the mural decoration illustrated in the drawing, for instance, certain figures and decorations are incised, formed, and produced according to this invention. 5 designates certain cuts in an otherwise evenly flat or level surface 6, as particularly brought out in the cross-section of Fig. 3.

50 Cuts or markings of this type serve to create desired shadows, or even slightly varied shading

of similarly colored portions of a design in an ornament, by and when lights are played on or over the ornaments.

On this particular decoration, however, the cuts 5 were produced in certain set-off sections 7, which were even differently colored than the back-ground at 6.

Similar cuts, on the other hand, are indicated at 8 in a large field together with outlines 9, in form of a dog, also incised, and, though the coloring of the larger portion of this field and the representation of the dog are of the same shade as such, the outline of the dog at 9 together with the cuts at 8, running all in the same direction, produce an easily distinguishable shade-effect when light is played on this surface in a suitable manner and direction.

Other outlines and cuts at 10, bringing out the form of a girl, are furthermore made distinct by a difference of colors, the figure of the girl, 20 in this case, being supplied with silver-leaf coloring while the larger surrounding field is merely colored yellow. Gold leaf may, however, also be used. Set-off lines 11 are used within the outer contours of the Figure 10, which are similarly 25 cut in, to result in a desired shade-effect.

As clearly illustrated in the several cross-sections, cuts and outlines are made very distinct so as to create distinct shade-effects when light plays upon or over the various surfaces and figures. The enlarged sections are made to bring out this feature of this invention, though it is not meant to convey any particular proportioning of the cuts and outlines with respect to the forms or figures, the cuts in the sectional views eventually being overemphasized, while, in the illustration of Fig. 1, the same cuts and outlines are merely shown in single lines for the sake of not overcrowding the illustration in Fig. 1 only and not that it should be interpreted that no distinct cuts were provided.

30 Having the cuts indicated in rather broad triangular forms in the cross sectional views, furthermore, should not create the impression that these cuts of necessity are required to be 45 in this form, but again this is done only for the sake of clearness in the drawing, while these cuts may be of very narrow form, the desired figures and forms and decorations being merely incised wide and deep enough to stand out after being coated with paint or leaf material.

50 Certain of the decorations or certain portions of a decoration are furthermore not only outlined as set forth above but also shaped and even raised over the surfaces of other portions, as clearly illustrated in the cross sectional views with respect to the portions 6, 13, 14, 12, 17, 18 and 15.

55 The large triangles 14, for instance, are raised distinctly over the incised back-ground next to 60

the triangles, the edges 12 in Figs. 1 and 4 clearly bringing out this feature.

Though a certain color-scheme has been indicated by a shading of Fig. 1, it, of course, should be understood that any other color-scheme could have been used, depending on the taste of the artist or customer to a large extent.

Having thus described my invention, I claim:—

- 10 1. The process of decorating consisting in handling the material in a surface to be decorated in a plastic state while in place, outlining figures and decorations in the surface by making impressions and raising the material in the surface at points, applying decorating material to the surface, and building up decorations above the first outlined decorations.
- 20 2. The process of decorating consisting in handling the material in a surface to be decorated in a plastic state while in place, outlining figures and decorations in the surface by making incisions, applying decorating material to the surface, building up decorations above the outlined decorations in the surface, and applying decorating material to the raised and built up portions.

3. The process of decorating consisting in handling the material in a surface to be decorated in a plastic state while in place, producing shade-effects in form of and for ornamental representations by inscribing, engraving, and scratching into the plastic surface, emphasizing the representations by producing other shade effects in form of and representing back-ground by inscribing, engraving, and scratching into the surface, and applying decorating material co-effective with such producing of shade-effects.

4. The process of producing mural decorations consisting in handling the material in a surface to be decorated in a plastic state while in place, then producing ornaments and figures by inscribing, engraving, and cutting shade-effects together with an application of decorating material with respect to such plastic surface, and then producing a back-ground with respect to the ornaments and figures by inscribing, engraving, and cutting shade-effects together with an application of decorating material in such plastic surface.

ANTHONY B. HEINSBERGEN.
